UNITED STATES PATENT OFFICE.

JOHN MURPHY, OF SPRINGFIELD, MASSACHUSETTS.

BRIDLE-BIT.

SPECIFICATION forming part of Letters Patent No. 297,944, dated April 29, 1884.

Application filed August 8, 1883. (No model.)

To all whom it may concern:

Be it known that I, JOHN MURPHY, a citizen of the United States, residing at Springfield, Hampden county, State of Massachusetts, 5 have invented a new and useful Improvement in Bridle-Bits, of which the following is a specification.

This invention relates to an improved method of uniting and hinging the cheek-piece to the mouth-piece; and it consists, in brief, of adapting the cheek-piece to admit of a screw-pin uniting these sections and forming the hinge-pin, by means of which the many difficulties incident to annealing and finishing bits 15 made in the ordinary way are obviated. The wear of the hinge-surfaces can be taken up, the hinge-pin can be renewed at small cost, and, without removing the cheek-straps or reins from the rings, different mouth-pieces may be 20 combined with the same cheek-pieces. This is fully illustrated in the accompanying drawings, in which—

Figure I is a side elevation, in partial section, of a stiff bit of my construction; and Fig. 25 II is a plan view of one-half of a snaffle-bit, with its cheek-piece removed.

B is the ring cheek-piece, slotted at *b* to receive the end *d* of the mouth-piece D. The cheek-piece is bored in prolongation of the 30 hole *h* in the mouth-piece end, to receive the pin H, and to afford a screw-socket below the

mouth-piece, to receive the screw end of the pin H, as seen in Fig. I; and I prefer, as shown, to receive the head of pin H in a counter-bore in the cheek-piece. The bore which receives the pin H is elongated, as shown in the drawings, so that it is longer than said pin; and when the jaws of the cheek-ring are distended to their maximum extent, there will be a space, *x*, left below the screw, thus permitting the said jaws to be drawn together by simply turning the screw-pin H. The spring in the ring of the cheek-piece permits the mouth-piece, by means of screw H, to be always so snugly clamped that while the hinge 45 is unimpaired no dirt can get in the joint, nor moisture to freeze.

Now, having described my invention, what I claim as new is—

In a bridle-bit, a ring cheek-piece slotted to 50 form jaws, between which the apertured end of the bit-bar is clamped, said jaws having a countersunk and tapped bore to receive a headed screw-pin, said bore being elongated beyond the length of the pin, so that when 55 the jaws are distended to their maximum extent there will be a space below the point of the screw-pin, substantially as set forth.

JOHN MURPHY.
